(57) **ABSTRACT**

A micro analysis chip comprises an inlet and a fluid flow path communicating thereto. The fluid flow path comprises a first flow path, a second flow path, and a third flow path arranged continuously along a longitudinal direction of the fluid flow path. An antibody is bound on at least one peripheral surface selected from the group consisting of peripheral surfaces of the second and third flow paths. A cross-sectional area of the third flow path is constant or increased monotonically along a direction X from the second flow path toward the third flow path. A cross-sectional area of the second flow path is increased monotonically along the direction X from the one end to the other end of the second flow path. A cross-sectional area of the first flow path is constant or increased monotonically along the direction X from the one end to the other end of the first flow path.

(Continued)

path is larger than a cross-sectional area at the one end of the second flow path.

MICRO ANALYSIS CHIP AND FABRICATION METHOD THEREOF

CROSS-REFERENCE TO RELATED APPLICATIONS

This is a continuation application of International Application No. PCT/JP2016/003655, with an international filing date of Aug. 8, 2016, which claims priority of Japanese Patent Application No. 2015-163050 filed on Aug. 20, 2015, the content of which is incorporated herein by reference.

BACKGROUND OF THE INVENTION

1. Technical Field

The technical field relates to a micro analysis chip and a fabrication method thereof.

2. Description of Related Art

FIG. 10 is a duplicate of FIG. 5 included in Japanese Patent Application laid open Unexamined Publication No. 2009-047485A, which discloses a microinspection chip and inspection device. In this document, a microinspection chip 800 is prepared first. The microinspection chip 800 has a mixed liquid flow channel 141, an amplifying part 811, and a drain flow channel 151. The amplifying part 811 has a wall 811a and a wall 811b close to the mixed liquid flow channel 141 and the drain flow channel 151, respectively. The wall 811 and the wall 811b face each other.

A mixture of a liquid 123 and a liquid 133 is supplied from the mixed liquid flow channel 141 to the amplifying part 811 in such a manner that an interface 161 of the mixture is not in contact with the wall 811b. Then, the mixture is heated with a heater 223 to obtain a product liquid 161. The product liquid 161 located on a detection region 255 included in the amplifying part 811 is analyzed using a detection part 250 including a light source 251 and a light-receiving element 253. Finally, the valve is open to drain the product liquid 161 through the drain flow channel 151.

SUMMARY

One non-limiting and exemplary embodiment provides a fabrication method thereof.

In one general aspect, the techniques disclosed here feature: a method for fabricating a micro analysis chip, the method including:

(a) providing a first substrate comprising a fluid flow path; wherein

the fluid flow path comprises a first flow path, a second flow path, and a third flow path which are arranged continuously along a longitudinal direction of the fluid flow path;

the second flow path has one end and another end;

the first flow path communicates with the second flow path through the one end of the second flow path;

the second flow path is interposed between the first flow path and the third flow path;

the second flow path communicates with the third flow path through the other end of the second flow path;

a cross-sectional area of the third flow path is constant or increased monotonically along a direction X from the first flow path toward the second flow path in the top view of the first substrate;

a cross-sectional area of the second flow path is increased monotonically along the direction X from the one end to the other end of the second flow path in the top view of the first substrate; and

5 a cross-sectional area of the first flow path is larger than a cross-sectional area at the one end of the second flow path in the top view of the first substrate;

(b) dropping an aqueous solution containing an antibody onto a peripheral surface of the second flow path;

10 wherein
the following relation (IAA) is satisfied:

$$LS \leq L2 + L3 \quad (\text{IAA})$$

where

15 LS represents the length of the aqueous solution from the one end of the second flow path along the longitudinal direction of the fluid flow path;

L2 represents the length of the second flow path along the longitudinal direction in the fluid flow path; and

20 L3 represents the length of the third flow path along the longitudinal direction in the fluid flow path; and

(c) drying the aqueous solution to bind the antibody to the peripheral surface of the second flow path;

wherein

25 one end of the aqueous solution is located at the one end of the second flow path;

the other end of the aqueous solution moves along a direction opposite to the direction X;

the antibody is immobilized on the peripheral surface of the second flow path; and

30 the following relation (IBB) is satisfied:

$$LA < LS' < LS \quad (\text{IBB})$$

where

35 LA represents a distance between the antibody immobilized on the peripheral surface of the second flow path and the one end of the second flow path; and

LS' represents the length of the aqueous solution in the step (c).

40 Additional benefits and advantages of the disclosed embodiments will be apparent from the specification and figures. The benefits and/or advantages may be individually provided by the various embodiments and features of the specification and drawings disclosure, and need not all be provided in order to obtain one or more of the same.

BRIEF DESCRIPTION OF DRAWINGS

The present disclosure will become readily understood from the following description of non-limiting and exemplary embodiments thereof made with reference to the accompanying drawings, in which like parts are designated by like reference numeral and in which:

FIG. 1A shows a cross-sectional view of a micro analysis chip according to an embodiment;

55 FIG. 1B shows a top view of the micro analysis chip;

FIG. 2 shows a top view of the micro analysis chip in which a liquid sample has been supplied to the fluid flow path in a step (b);

60 FIG. 3A shows a cross-sectional view in one step included in a method for fabricating the micro analysis chip according to the embodiment;

FIG. 3B shows a top view in one step included in a method for fabricating the micro analysis chip according to the embodiment;

65 FIG. 4 shows a cross-sectional view in one step included in a method for fabricating the micro analysis chip according to the embodiment;

FIG. 5A shows a top view in one step, subsequent to FIG. 4, included in a method for fabricating the micro analysis chip according to the embodiment;

FIG. 5B shows a top view in one step, subsequent to FIG. 5A, included in a method for fabricating the micro analysis chip according to the embodiment;

FIG. 5C shows a top view in one step, subsequent to FIG. 5B, included in a method for fabricating the micro analysis chip according to the embodiment;

FIG. 6 shows a top view in one step, subsequent to FIG. 5C, included in a method for fabricating the micro analysis chip according to the embodiment;

FIG. 7 shows a top view in one step, subsequent to FIG. 6, included in a method for fabricating the micro analysis chip according to the embodiment;

FIG. 8 shows a cross-sectional view in one step, subsequent to FIG. 7, included in a method for fabricating the micro analysis chip according to the embodiment;

FIG. 9A shows a top view in one step included in a method for fabricating a conventional micro analysis chip;

FIG. 9B shows a top view in one step included in a method for fabricating a conventional micro analysis chip;

FIG. 9C shows a top view in one step included in a method for fabricating a conventional micro analysis chip; and

FIG. 10 is a duplicate of FIG. 5 included in Japanese Patent Application Unexamined Publication No. 2009-047485A.

DETAILED DESCRIPTION

Hereinafter, the embodiment of the present invention will be described with reference to the drawings.

(Micro Analysis Chip)

First, a micro analysis chip according to the present embodiment will be described. The micro analysis chip is used for Micro-Total Analysis system (hereinafter, referred to as “μ-TAS”) in which an ingredient included in a small amount of a liquid sample is analyzed. An example of the liquid sample is blood, urine, or sweat obtained from an animal including a human.

FIG. 1A shows a cross-sectional view of the micro analysis chip 100 used in the embodiment. The micro analysis chip 100 comprises an upper substrate 150 and a lower substrate 160, as shown in FIG. 1A. The lower substrate 160 and the upper substrate 150 may be referred to as a first substrate and a second substrate, respectively. FIG. 1B shows a top view of the micro analysis chip 100. To be exact, FIG. 1B shows a top view of the lower substrate 160. In FIG. 1B, the upper substrate 150 is omitted.

The back surface of the upper substrate 150 adheres to the front surface of the lower substrate 160, as shown in FIG. 1A. The upper substrate 150 comprises an inlet 102 and an outlet 106. The inlet 102 and the outlet 106 penetrate the upper substrate 150. The lower substrate 160 comprises a fluid flow path 104 on the surface thereof. The fluid flow path 104 communicates with the inlet 102 and the outlet 106. Since the fluid flow path 104 is narrow, capillary force occurs in the fluid flow path 104.

As just described, the micro analysis chip 100 comprises the inlet 102, the fluid flow path 104, and the outlet 106. The liquid sample is supplied to the inlet 102. Then, the liquid sample held on the fluid flow path 104 is analyzed. Finally, the liquid sample is drained from the fluid flow path 104 through the outlet 106.

In FIG. 1A and FIG. 1B, the fluid flow path 104 is formed on the front surface of the lower substrate 160. Alternatively,

the fluid flow path 104 may be formed on the back surface of the upper substrate 150. In addition, the fluid flow path 104 may be formed on both of the back surface of the upper substrate 150 and the front surface of the lower substrate 160. In this case, the fluid flow path formed on the back surface of the upper substrate 150 has the same shape as the fluid flow path formed on the front surface of the lower substrate 160.

As shown in FIG. 1B, the fluid flow path 104 comprises a first flow path 104a, a second flow path 104b, and a third flow path 104c. These paths are arranged continuously along the longitudinal direction of the fluid flow path 104.

The second flow path 104b has one end 104b1 and the other end 104b2 at the sides of the inlet 102 and the outlet 106, respectively.

The first flow path 104a is interposed between the inlet 102 and the second flow path 104b. The first flow path 104a communicates with second flow path 104b through the one end 104b1 of the second flow path 104b.

The second flow path 104b is interposed between the first flow path 104a and the third flow path 104c. The second flow path 104b communicates with the third flow path 104c through the other end 104b2 of the second flow path 104b.

As just described, since the first flow path 104a and the second flow path 104b are arranged continuously along the longitudinal direction of the fluid flow path 104, another flow path is absent between the first flow path 104a and the second flow path 104b. In other words, the first flow path 104a communicates with the second flow path 104b directly.

Similarly, another flow path is absent between the second flow path 104b and the third flow path 104c. In other words, the second flow path 104b communicates with the third flow path 104c directly.

Capillary force may occur in all of the first-third flow paths 104a-104c. In the present invention, capillary force occurs in at least the second flow path 104b, since the second flow path 104b includes a part having the smallest cross-sectional area in the fluid flow path 104 (i.e., the one end 104b1 of the second flow path 104b).

The fluid flow path 104 is surrounded by a wall surface of a groove 152 formed on the lower substrate 160 and the back surface of the upper substrate 150. For this reason, the second flow path 104b and the third flow path 104c are also surrounded by a wall surface of the groove 152 formed on the lower substrate 160 and the back surface of the upper substrate 150. An antibody is immobilized on the wall surface of the groove 152 or the back surface of the upper substrate 150 in such a manner that the antibody is located on the peripheral surface of the second flow path 104b or the third flow path 104c. The region in which the antibody is immobilized is referred to as an antibody region 105. In FIG. 1B, the antibody region 105 is located in both of the second flow path 104b and the third flow path 104c. Alternatively, the antibody region 105 may be formed on either the second flow path 104b or the third flow path 104c.

The cross-sectional area of the second flow path 104b increases monotonically along the direction from the second flow path 104b toward the third flow path 104c. In other words, the cross-sectional area of the second flow path 104b increases monotonically along a direction X depicted in FIG. 1B (i.e., the direction indicated by an arrow X) from the one end 104b1 to the other end 104b2 of the second flow path 104b. As one example, the width W2 of the second flow path 104b increases monotonically along the direction X.

Alternatively, the height H2 (See FIG. 1A) of the second flow path 104b may increase monotonically along the direction X. Both of the width W2 and the height H2 of the

second flow path **104b** may increase monotonically along the direction X. The second flow path **104b** does not comprise a part in which its cross-sectional area is constant along the direction X. Similarly, the second flow path **104b** does not comprise a part in which its cross-sectional area is decreased along the direction X.

On the other hand, the cross-sectional area of the third flow path **104c** is constant or increased monotonically along the direction X. It is desirable that the cross-sectional area of the third flow path **104c** increase monotonically along the direction X, as one example, the width W3 of the third flow path **104a** increases monotonically along the direction X. Alternatively, the height H3 (See FIG. 1A) of the third flow path **104c** may increase monotonically along the direction X.

The cross-sectional area of the first flow path **104a** is larger than the cross-sectional area at the one end **104b1** of the second flow path **104b**. This is important. The reason will be described later.

As one example, the fluid flow path **104** suitable for μ -TAS may have lengths and widths as below.

Length L1 of the first flow path **104a**: 10 micrometers-5000 micrometers

Width W1 of the first flow path **104a**: 10 micrometers-500 micrometers

Length L2 of the second flow path **104b**: 10 micrometers-500 micrometers

Width W2 of the second flow path **104b**: 10 micrometers-500 micrometers

Length L3 of the third flow path **104c**: 10 micrometers-5000 micrometers

Width W3 of the third flow path **104c**: 10 micrometers-500 micrometers

It is desirable that the fluid flow path **104** does not have a part in which its cross-sectional area is decreased along the direction X between the third flow path **104c** and the outlet **106**. As one example, as shown in FIG. 1B, the third flow path **104c** communicates directly with the outlet **106**.

(Method for Fabricating the Micro Analysis Chip)

Hereinafter, a method for fabricating the above-mentioned micro analysis chip will be described with reference to FIG. 3A-FIG. 8.

First, a groove is formed on a surface of a substrate having a certain thickness to form the fluid flow path **104** on the surface thereof. The groove is formed by a photolithography method or an etching method. In this way, the lower substrate **160** as shown in FIG. 3A and FIG. 3B is prepared. In FIG. 3A and FIG. 3B, the inlet **102** and the outlet **106** are formed in the lower substrate **160**. However, as shown in FIG. 1A and FIG. 1B, the inlet **102** and the outlet **106** may be formed in the upper substrate **150**.

(Step (a))

Next, as shown in FIG. 4, an aqueous solution containing an antibody is dropped as a droplet **301** toward the lower substrate **160**. The droplet **301** is supplied to the second flow path **104b**. It is desirable that the droplet **301** is dropped onto the second flow path **104b**. The droplet **301** may be dropped onto the third flow path **104c**. In this way, as shown in FIG. 5A, the aqueous solution **302** containing the antibody is supplied to the second flow path **104b**. The droplet **301** may have a volume of 10 picoliters-10 nanoliters.

(Step (b))

The droplets **301** may be dropped towards to the lower substrate **160** more than once. As shown in FIG. 5B, the aqueous solution **302** is spread onto the peripheral surface of the second flow path **104b**. Finally, as shown in FIG. 5C, the

aqueous solution **302** is also spread onto the peripheral surface of the third flow path **104c**. One droplet **301** may be dropped toward the lower substrate **160** to spread the aqueous solution **302** onto the fluid flow path **104**, as shown in FIG. 5C.

In the step (b), the following relation (IAA) is satisfied:

$$LS \leq L2 + L3 \quad (\text{IAA})$$

where

LS represents the length of the liquid sample from the one end of the second flow path along the longitudinal direction of the fluid flow path;

L2 represents the length of the second flow path along the longitudinal direction in the fluid flow path; and

L3 represents the length of the third flow path along the longitudinal direction in the fluid flow path.

The aqueous solution has one end **302a** and the other end **302b**.

It is desirable that the following relation (II) is satisfied:

$$LS < L2 + L3 \quad (\text{II})$$

The aqueous solution **302** hardly is spread to the first flow path **104a**, since the cross-sectional area of the first flow path **104a** is larger than the cross-sectional area at the one end **104b1** of the second flow path **104b**. Since the cross-sectional area of the second flow path **104b** is increased monotonically along the direction X, the aqueous solution **302** contained in the second flow path **104b** is pulled toward a direction opposite to the direction X due to capillary force. Hereinafter, the direction opposite to the direction X is referred to as “-X direction”

Since the cross-sectional area of the first flow path **104a** is larger than the cross-sectional area at the one end **104b1** of the second flow path **104b**, the capillary force generated in the first flow path **104a** is smaller than the capillary force generated in the second flow path **104b**. For this reason, the aqueous solution which has reached the one end **b1** of the second flow path **104b** is not spread onto the first flow path **104a**.

In case where the cross-sectional area of the first flow path **104a** is equal to or smaller than the cross-sectional area of the one end **104b1** of the second flow path **104b**, the capillary force generated in the first flow path **104a** is equal to or larger than the capillary force generated in the second flow path **104b**, the aqueous solution which has reached the one end **b1** of the second flow path **104b** is spread onto the first flow path **104a**. The present invention does not include such a case.

The aqueous solution **302** is supplied to the fluid flow path **104** in this way is brought into contact with the second flow path **104b** and the third flow path **104c**.

Next, as shown in FIG. 8, the aqueous solution **302** is dried. The aqueous solution **302** may be dried naturally. Alternatively, the aqueous solution **302** is warmed to promote the drying.

(Step (c))

Next, as shown in FIG. 6, the aqueous solution **302** is left at rest. The aqueous solution **302** is dried naturally. Alternatively, the lower substrate **160** was stored under a humidified atmosphere to prevent the drying of the aqueous solution **302** at minimum.

As a result, as shown in FIG. 6, the volume of the aqueous solution **302** is decreased. In other words, the following relation (IBB) is satisfied.

$$LA < LS' < LS \quad (\text{IBB})$$

where

LA represents a distance between an analysis region 170 and the one end 104b1 of the second region 104b; and

LS' represents the length from the one end 104b1 of the second flow path 104b to the other end 302b of the aqueous solution 302 along the direction X after the aqueous solution 302 is left at rest (See FIG. 6).

Hereinafter, a problem in a case where the cross-sectional area of the flow path is constant will be described with reference to FIG. 9A, FIG. 9B, and FIG. 9C. As shown in FIG. 9A, the aqueous solution 302 containing the antibody is supplied to a flow path 904. Next, the aqueous solution 302 is dried to form an antibody region covering the analysis region 170. However, since the cross-sectional area of the flow path is constant, the aqueous solution 302 moves either rightward or leftward, while the aqueous solution 302 is dried. For this reason, as shown in FIG. 9B and FIG. 9C, the aqueous solution 302 may fail to cover the analysis region 170. As a result, the antibody region may fail to be formed on the analysis region 170.

On the other hand, in the present embodiment, the aqueous solution 302 is pulled along the -X direction due to capillary force as shown in FIG. 6, since the cross-sectional area of the second flow path 104b is monotonically increased along the direction X. In other words, since the cross-sectional area of the second flow path 104b is monotonically decreased along the -X direction, the aqueous solution 302 is pulled along the -X direction. In this way, one end 302a of the aqueous solution 302 is always positioned at the one end 104b1 of the second flow path 104b.

While the aqueous solution 302 is dried, the other end 302b of the aqueous solution 302 moves along the -X direction. However, the aqueous solution 302 is surely present at the one end 104b1 of the second flow path 104b. This is because the capillary force is generated along the -X direction in the second flow path 104b.

As previously described, since the cross-sectional area of the first flow path 104a is larger than the cross-sectional area of the one end 104b1 of the second flow path 104b, the aqueous solution 302 which has reached the one end 104b1 of the second flow path 104b is not spread onto the first flow path 104a.

For this reason, in the present invention, it is necessary that the cross-sectional area of the first flow path 104a is larger than the cross-sectional area of the one end 104b1 of the second flow path 104b.

In this way, as shown in FIG. 7, the antibody region 105 is surely formed on the peripheral surface of the second flow path 104b. Before the aqueous solution 302 is dropped toward the lower substrate 160, the lower substrate 160 may be subjected to a surface treatment. The surface treatment allows the antibody to be easily immobilized on the lower substrate. Such a surface treatment is well-known.

(Step (d))

Finally, as shown in FIG. 8, the upper substrate 150 is arranged as a lid onto the lower substrate 160. In this way, the micro analysis chip according to the present embodiment is fabricated.

(Method for Analyzing with the Micro Analysis Chip)

Next, a method for analyzing a liquid sample containing an antigen using the above-mentioned micro analysis chip will be described.

As shown in FIG. 2, the liquid sample 140 is supplied from the inlet 102 to the fluid flow path 104.

For one example, the liquid sample 140 provided for a μ -TAS is supplied from the inlet 102 at a flow rate of 0.01 microliter/minute to 2 microliters/minute.

As a result, the liquid sample 140 is brought into contact with the antibody immobilized on the analysis region 170 included in the antibody region 105. Since the analysis region 170 is arranged at at least one of the second flow path 104b and the third flow path 104c, at least a part of the liquid sample 140 is required to be supplied to the second flow path 104b.

The antigen contained in the liquid sample 140 is bound to the antibody immobilized on the analysis region 170.

Then, the antigen bound to the antibody immobilized on the analysis region 170 included in at least one of the second flow path 104b and the third flow path 104c is analyzed. The analysis method is not limited. As one example, the antigen included in the liquid sample 140 is analyzed optically or electrochemically. Before the analysis of the antigen, a contamination present on the analysis region 170 may be removed by, for example, washing.

The present invention can be used to analyze the liquid sample obtained from a research participant near the research participant.

The inventions led from the above description will be listed below.

1. A method for fabricating a micro analysis chip, the method comprising:

(a) supplying an aqueous solution containing an antibody to a first substrate comprising a fluid flow path; wherein the fluid flow path comprises a first flow path, a second flow path, and a third flow path which are arranged continuously along a longitudinal direction of the fluid flow path;

the second flow path has one end and another end;

the first flow path communicates with the second flow path through the one end of the second flow path;

the second flow path is interposed between the first flow path and the third flow path;

the second flow path communicates with the third flow path through the other end of the second flow path;

a cross-sectional area of the third flow path is constant or increased monotonically along a direction X from the second flow path toward the third flow path;

a cross-sectional area of the second flow path is increased monotonically along the direction X from the one end to the other end of the second flow path;

a cross-sectional area of the first flow path is larger than a cross-sectional area at the one end of the second flow path; and

the aqueous solution is supplied to the second flow path;

(b) bringing the aqueous solution into contact with an analysis region included in at least one of the second flow path and the third flow path;

wherein

the following relation (IAA) is satisfied:

$$LS \leq L2 + L3 \quad (IAA)$$

where

LS represents the length of the liquid sample from the one end of the second flow path along the longitudinal direction of the fluid flow path;

L2 represents the length of the second flow path along the longitudinal direction in the fluid flow path; and

L3 represents the length of the third flow path along the longitudinal direction in the fluid flow path; and

(c) leaving the aqueous solution at rest;

wherein

one end of the aqueous solution is located at the one end of the second flow path;

the other end of the aqueous solution moves along a direction opposite to the direction X;
the antibody is immobilized on the analysis region; and
the following relation (IBB) is satisfied:

$$LA < LS' < LS \quad (IBB)$$

where

LA represents a distance between the analysis region and the one end of the second region; and

LS' represents the length of the liquid sample in the step (c).

2. The method according to Item 1, wherein
the following relation (II) is satisfied.

$$LS < L2 + L3$$

3. The method according to Item 1, wherein
the aqueous solution is also supplied to the third flow path
in the step (a).

4. The method according to Item 1, further comprising:
(d) arranging a second substrate as a lid onto the lower
substrate, after the step (c).

5. A micro analysis chip comprising:
an inlet; and
a fluid flow path which communicates with the inlet;
wherein

the fluid flow path comprises a first flow path, a second
flow path, and a third flow path which are arranged con-
tinuously along a longitudinal direction of the fluid flow
path;

the second flow path has one end and another end;
the first flow path is interposed between the inlet and the
second flow path;

the first flow path communicates with the second flow
path through the one end of the second flow path;

the second flow path is interposed between the first flow
path and the third flow path;

the second flow path communicates with the third flow
path through the other end of the second flow path;

an antibody is bound on at least one peripheral surface
selected from the group consisting of a peripheral surface of
the second flow path and a peripheral surface of the third
flow path;

a cross-sectional area of the third flow path is constant or
increased monotonically along a direction X from the sec-
ond flow path toward the third flow path;

a cross-sectional area of the second flow path is increased
monotonically along the direction X from the one end to the
other end of the second flow path; and

a cross-sectional area of the first flow path is larger than
a cross-sectional area at the one end of the second flow path.

6. The micro analysis chip according to Item 5, wherein
the micro analysis chip further comprises an outlet;
the fluid flow path is interposed between the inlet and the
outlet; and

the fluid flow path does not comprises, between the third
flow path and the outlet, a part in which its cross-sectional
area is decreased along a direction from the second flow path
to the third flow path.

7. A method for analyzing a liquid sample containing an
antigen, the method comprising:

(a) preparing a micro analysis chip; wherein

the micro analysis chip comprises:

an inlet; and

a fluid flow path which communicates with the inlet;

the fluid flow path comprises a first flow path, a second
flow path, and a third flow path which are arranged con-
tinuously along a longitudinal direction of the fluid flow
path;

5 the second flow path has one end and another end;
the first flow path is interposed between the inlet and the
second flow path;

the first flow path communicates with the second flow
path through the one end of the second flow path;

10 the second flow path is interposed between the first flow
path and the third flow path;

the second flow path communicates with the third flow
path through the other end of the second flow path;

an antibody is immobilized on at least one peripheral

15 surface selected from the group consisting of a peripheral
surface of the second flow path and a peripheral surface of
the third flow path;

a cross-sectional area of the third flow path is constant or
increased monotonically along a direction X from the sec-
ond flow path toward the third flow path;

20 a cross-sectional area of the second flow path is increased
monotonically along the direction X from the one end to the
other end of the second flow path;

a cross-sectional area of the first flow path is larger than

25 a cross-sectional area at the one end of the second flow path;
and

a cross-sectional area of the first flow path is larger than
a cross-sectional area of the one end of the second flow path;

(b) supplying the liquid sample from the inlet to the fluid

30 flow path to bring the liquid sample into contact with the
antibody and to bind the antigen contained in the liquid
sample to the antibody, while the liquid sample is hold in the
second flow path, and

(c) analyzing the antigen bound to the antibody immobi-

35 lized on the analysis region included in the second flow path
and the third flow path.

8. The method according to Item 7, wherein

the micro analysis chip further comprises an outlet;

the fluid flow path is interposed between the inlet and the
40 outlet; and

the fluid flow path does not comprises, between the third
flow path and the outlet, a part in which its cross-sectional
area is decreased along a direction from the second flow path
to the third flow path.

What is claimed is:

1. A method for fabricating a micro analysis chip, the
 method comprising:
 (a) providing a substrate comprising a fluid flow path;
 wherein:
 the fluid flow path comprises a first flow path, a second
 flow path, and a third flow path which are arranged
 continuously along a longitudinal direction of the fluid
 flow path;
 the second flow path has one end and another end;
 the first flow path communicates with the second flow
 path through the one end of the second flow path;
 the second flow path is interposed between the first flow
 20 path and the third flow path;
 the second flow path communicates with the third flow
 path through the other end of the second flow path;
 a width of the third flow path is constant or increases
 monotonically along a direction X from the first flow
 path toward the second flow path in a top view of the
 substrate;
 a width of the second flow path increases monotonically
 25 along the direction X from the one end of the second
 flow path to the other end of the second flow path in the
 top view of the substrate; and

12

a width of the first flow path is larger than the width of the
 second flow path at the one end of the second flow path
 in the top view of the substrate;

- (b) dropping an aqueous solution containing an antibody
 onto a peripheral surface of the second flow path;
 wherein:

a relation $LS \leq L2 + L3$ is satisfied,

where:

LS represents a length of the aqueous solution from the
 one end of the second flow path along the longitudinal
 direction of the fluid flow path;

L2 represents a length of the second flow path along the
 longitudinal direction of the fluid flow path; and

L3 represents a length of the third flow path along the
 longitudinal direction of the fluid flow path; and

- (c) drying the aqueous solution to bind the antibody to the
 peripheral surface of the second flow path;

wherein:

one end of the aqueous solution is located at the one end
 of the second flow path;

another end of the aqueous solution moves along a
 direction opposite to the direction X;

the antibody is immobilized at least partially on an
 analysis region on the fluid flow path; and

a relation $LA < LS' < LS$ is satisfied,

where:

LA represents a distance between the one end of the
 second flow path and an end of the analysis region
 farthest from the one end of the second flow path; and
 LS' represents the length of the aqueous solution as a
 result of the step (c).

2. The method according to claim 1, wherein:

a relation $LS < L2 + L3$ is satisfied.

3. The method according to claim 1, wherein:

the aqueous solution is also dropped onto a peripheral
 surface of the third flow path in the step (b).

4. The method according to claim 1, wherein the substrate
 is a first substrate and the method further comprises:

(d) arranging a second substrate as a lid onto the first
 substrate, after the step (c).
